DISPLAY STAND OR SIMILAR ARTICLE

Jay F. Schweickart, deceased, late of Lancaster, Ohio, by Beverly J. Schweickart, administratrix, Lancaster, Ohio, assignor to Anchor Hocking Corporation, Lancaster,
Ohio

Filed Feb. 17, 1970, Ser. No. 21,464

Term of patent 14 years

Int. Cl. D6—06

U.S. Cl. D80—9

FIG. 1 is a perspective view of a display stand or similar article showing my new design;

FIG. 2 is an elevational view taken from one end thereof;

FIG. 3 is an elevational view taken from the end opposite that shown in FIG. 2;

FIG. 4 is a top plan view thereof; and

FIG. 5 is a sectional view taken along line 5—5 of FIG. 1.

I claim:

The ornamental design for a display stand or similar article, substantially as shown.
